ATTORNEYS

UNITED STATES PATENT OFFICE.

WILLIAM J. MCGALL, OF WEST ORANGE, NEW JERSEY, ASSIGNOR TO
LUDOVIC MCGALL, OF SAME PLACE.

HAT-BRIM-CURLING MACHINE.

SPECIFICATION forming part of Letters Patent No. 593,810, dated November 16, 1897.

Application filed July 27, 1896. Serial No. 600,615. (No model.)

To all whom it may concern:

Be it known that I, WILLIAM J. MCGALL, a citizen of the United States, residing at West Orange, in the county of Essex and State of New Jersey, have invented certain new and useful Improvements in Hat-Curling Machines; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The objects of this invention are to simplify the construction of hat-curling machines and reduce the cost thereof, to provide a device that will be more convenient to the operator and give him greater control of the hat when 20 curling the same, to provide a device that will admit of the curl being made to extend closer to the body of the hat than can be secured when a rotating shaft having a convex curling wheel or button is disposed between the 25 curled edge of the brim and the body of the hat, and to secure other advantages and results, some of which will be referred to hereinafter in connection with the description of the working parts.

30 The invention consists in the improved hat-curling machine and in the arrangements and combinations of parts thereof, all substantially as will be hereinafter set forth, and finally embraced in the clauses of the claim.

35 Referring to the accompanying drawings, in which like letters of reference indicate corresponding parts in both views, Figure 1 is a vertical section of the machine, illustrating my invention, the section being taken on line 40 x of Fig. 2. Fig. 2 is a plan of a portion of the said machine.

The invention relates more particularly to that class of hat-curling machines represented by the one shown in my former patent, No. 45 480,877, of August 16, 1892.

In carrying out the invention I employ, in connection with a suitable table, bed, or frame a , of any desired form, arrangement, or construction, a revolving curling-frame b , having 50 at its upper part an annular inwardly-concavous rim or flange c , supported by arms d ,

extending up from a wheel-shaped part e , a hub f of which bears upon the frame or table a and is provided with an axle or shaft g , which last extends through the table or frame 55 and is provided on the under side of said table with a bevel gearing-wheel h . Said bevel gear-wheel h meshes with a co-operating bevel-wheel i on a shaft j with a power-pulley k , by means of which last and its connections power 60 is transmitted to the frame b to effect a rotation of said frame in a horizontal plane, preferably at a low rate of speed.

The concavous flange c may be modified in shape at will to suit the various shapes desired to be formed in or given to the curled hat-brim.

Co-operating with the concavous flange c is a stationary or a non-rotary ironing-tool l , which is provided with a hook-shaped extremity adapted to curl under the upper member and into the concavity of the flange c , as shown in Fig. 1. This tool slides in a suitable bearing of the frame a to or from said frame and normally presses toward the concavous flange 75 c , so as to force the hat-brim into the concavity thereof.

The elastic pressure desired is obtained by means of a spring m , which normally tends to draw the ironing-hook of the tool toward 80 said frame. A spring n , arranged beneath the said tool, tends to throw the latter upward, so that the lower part of the hook of the tool will press upward beneath the upper member of the concavous flange. The upward pressure on the hat is regulated by an adjusting-screw o , arranged in any suitable manner. To throw the tool away from the concavous flange c prior to arranging the hat-brim between or withdrawing it from the 90 parts, I may employ a lever p , which is connected by a rope or wire q with a pedal (not shown) or other suitable operating devices.

The tool l is kept at a high temperature by means of a gas-jet r , adapted to throw the 95 flame into a cup-like portion s of the tool. A steam-pipe t may throw a jet of steam against the felt of the hat as it passes between the curling parts.

The concavous flange c is raised considerably above the base of the frame b , so that the operator may enter his hand beneath the

hat as it passes into contact with the curling members of the machine, so as to guide the movements of the hat with greater ease and more perfectly control the curling operations.

5 The hooked or backwardly-turned extremity of the tool *l* is made wide, as shown in outline in Fig. 2, so that considerable ironing-surface is brought into contact with the felt of the hat, and the extreme edge of said tool 10 corresponds in convexity to the contiguous portion of the annular curve for the same reason. I prefer to roughen to some extent the concavous portion of the annular flange, so that the felt of the hat-brim is held there-to and thereby caused to rotate with the frame as they travel over the ironing-tool. The friction of the tool, taken in connection with the pressure produced by the springs, the heat of the flame, and the dampness and 20 heat of the steam, effects a very permanent curl to the hat-brim. I prefer to provide a support *w* for the hat at a point opposite where it is being curled. This relieves the operator from the weight of the hat and yet 25 allows of free manipulation.

As the fixed curling or non-rotary tool is quite thin where it passes between the inner edge of the upper member of the concavous flange and the hat-body, I am enabled to make 30 a very tight curl in the hat-brim, as will be apparent. The machine has thus greater scope in its ability to curl various styles of hats.

The operation of the machine is very simple. The frame *b* is given its rotary movement by the operating mechanism in the manner already described. The tool *l* is heated 35 by means of the gas-flame and the steam is conducted to the felt after the latter has been 40 adjusted between the curling parts. As the frame rotates, it draws the hat guided by the hands of the operator over said fixed ironing-

tool and the hat is given the desired shape around the outer edge of its brim.

Having thus described the invention, what 45 I claim as new is—

1. In a hat-curling machine, the combination with the rotary frame having an annular, concavous flange and arms *d*, supporting the same and raising said flange above the 50 base of said frame to admit the hands of the operator to pass between the base of said frame and the hat-brim, of a hooked tool having an edge corresponding in curve with that of the flange, a spring for holding said parts 55 in engagement with an elastic pressure and means for operating said frame, substantially as set forth.

2. In a hat-curling machine, the combination with the rotary frame, of a non-rotary ironing-tool coöperating therewith to curl the brim, a spring *m*, a gas-pipe, a steam-pipe *t*, and means for rotating said frame and throwing said tool from said frame against the power of said spring, substantially as and for the 65 purposes set forth.

3. In a hat-curling machine, the combination with the rotary frame, having a concavous and annular flange raised above the base of said frame, bevel-gears *h*, *i*, shaft *j* and power-pulley, a support *w*, to coöperate with the hands in holding the hat up to the said annular flange, and an ironing-tool *l*, spring *m*, and lever *p*, and means whereby the same may be operated, substantially as and for the 70 purposes set forth.

In testimony that I claim the foregoing I have hereunto set my hand this 17th day of July, 1896.

WILLIAM J. MCGALL.
